UNITED STATES PATENT OFFICE

ALVA OTIS HAMBLEN, OF FLINT, MICHIGAN

FISHING TOOL

Application filed June 6, 1928. Serial No. 283,222.

My invention relates to a fishing tool for use in the recovering of lost pump and drill rods or pipes in the so-called driven wells.

The main object is to provide a tool which 5 may be lowered over the rod to be pulled whereby it will grip the said rod so that the same may be drawn from the well.

Another object is to provide such a device with a plurality of gripping members which 10 will automatically swing together and grip the rod to be withdrawn substantially entirely around its circumference, thus providing a better grip upon the rod and allowing long sections of rod to be removed from 15 the well.

A further object is to provide such a tool which is easily removed from the rod when the same is withdrawn and which will be simple and strong in construction and effi- 20 cient in operation.

With these and other objects in view the invention resides in the novel construction and arrangement of the parts as hereinafter set forth and claimed.

25 In the drawing:

Figure 1 is a side elevation of my tool.

Figure 2 is a vertical section of my tool, two of the hinged jaw elements being shown partially swung outward and the retaining 30 band removed.

Figure 3 is a plan view of my tool; and

Figure 4 is a detail view in perspective of one of the gripping elements or teeth.

In practicing my invention I provide a 35 main body portion 1, formed of suitable metal, which is provided with a reduced extension 2 and a medial bore 3, the said extension 2 having threads 4 to receive the internally threaded end of a pipe (not shown) 40 used in lowering the tool into a well (not shown).

Four jaws 5 are hinged to the lower margin 45 6 of the body 1 by conventional hinges 7 and these jaws are arcuate in cross section and wedge shaped on a longitudinal section thru the axis of the assembly, as shown, so that the inner faces 8 thereof will form a conical or bell shaped mouth 9 for the reception of the rod to be pulled. The walls 50 of the mouth converge upwardly as shown

and so tend to guide the tool in lowering it over the upper end of the said rod being pulled. The jaws 5 are releasably held in the closed position by a circular retaining band 10 adapted to slidably fit downwardly 55 thereover and seat against the outer arcuate shoulders 11. A band 12 is fixed upon the extended portion 2 of the body 1 and a chain 13 has its ends secured in apertured tabs or ears 14 formed upon the bands 10 and 12 thus preventing the entire removal of the band 10 from the tool so that it might become lost, yet allowing it to be readily removed from engagement with the jaws 5 as 60 will be understood.

Gripping teeth or blades 15 are rigidly secured at their lower ends in any suitable manner, as by screws 16, to the inner faces 8 of the jaws 5 adjacent the lower margins thereof. The gripping teeth 15 are formed of heavy spring material and are adapted to converge inwardly and upwardly towards their gripping ends 17 as shown, the said teeth being concavo-convex in cross section to conform closely to the contour of the 75 rod which they engage. The upper ends 17 are beveled or sharpened somewhat to aid in obtaining a firm grip upon the rod being removed and as shown in Figure 3 the same will be engaged or gripped at four diametri- 80 cally opposite points which also facilitates the removal of the said rod.

In the use and operation of the device the tool is screwed on the end of a suitable pipe and with the hinged jaws 5 closed, is lowered 85 into the well. The flaring mouth 9 will slip downwardly over the end of the rod to be pulled and the gripping teeth 15 due to their being made of spring material will spring outward allowing the said rod to pass 90 the teeth. Then by pulling upward upon the tool by the attached pipe (not shown) the gripping teeth will grip the rod so that it may be pulled from the well as will be understood. When the rod is withdrawn from the well the tool is removed therefrom by sliding the band 10 upward so that the jaws 95 5 may be swung outward releasing the rod. It is obvious that any number of hinged jaws 100 may be used as desired.

Thus it will be seen that I provide a simple and easily operated tool which is very efficient in fulfilling its function.

While I have herein set forth a preferred embodiment of my invention, it is understood that I may vary the structural details thereof, within the scope of the appended claims.

I claim:

1. In a tool of the class described, a circular body portion having a threaded extension for the reception of an operating pipe, and a passageway for a drill rod, a plurality of jaws hinged to the lower margin of the body, the said jaws being arcuate in cross-section and wedge shaped longitudinally the narrow end being turned downwardly, a band adapted to slidably fit over the jaws to hold the same in the closed position and spring set gripping teeth or blades secured to the inner faces of the jaws and converging inwardly and upwardly.
2. In a tool of the character described, a body portion having a longitudinal passageway for a drill rod, a band or collar fixed thereon, a plurality of jaw elements hinged to the body, the said jaw elements being arcuate in cross section and wedge shaped with the narrow ends disposed downwardly, a retaining band adapted to slidably fit over the jaw elements, a connecting element connecting the said retaining band and the said fixed band or collar, and spring set means upon the jaw elements to grip a drill pipe or the like for pulling the same.
3. In a tool of the character described, a body portion having a longitudinal passageway for a drill rod, a plurality of jaws hingedly connected to the body portion, the inner faces of the said jaws converging upwardly and inwardly and a plurality of spring set pipe gripping teeth or blades upon the jaws, the said teeth also converging upwardly and inwardly and being concavo-convex in cross section.

45 In testimony whereof I affix my signature.

ALVA OTIS HAMBLEN.
